United States Patent Office

Des. 192,453

Patented Mar. 20, 1962

192,453

BOTTLE

Russell B. Wilhelm, Waterville, Ohio, assignor to Owens-Illinois Glass Company, Toledo, Ohio, a corporation of Ohio

Filed Dec. 2, 1960, Ser. No. 63,080

Term of patent 14 years

(Cl. D58—8)

The sides not shown are the same as those shown.

I claim:

The ornamental design for a bottle, substantially as shown and described.
